METHOD AND FURNACE FOR HEAT-TREATMENT OF SURFACE COATINGS ON CONTINUOUSLY MOVED STRIPS

Dag Nickelsen, Knut Anders Nilsen, and Johan Wleügel, Oslo, Norway, assignors to A/S Nordisk Aluminium-industri, Oslo, Norway

Application June 12, 1952, Serial No. 293,188

Claims priority, application Sweden June 13, 1951

6 Claims. (Cl. 117—103)

By heat treatment of surface coatings on strips which are moved continuously in their direction of length, for instance by heat hardening of lacquer coatings on metal strips, it is essential to try to obtain an effective heat transfer to the running strip in order to be able to operate at a great strip speed with an apparatus of a reasonable size, and thereby obtain an economical treatment. Further it is essential, when using a comparatively high strip speed to try to use a treatment temperature which does not unfavourably affect the characteristics of the strip and of the surface coating, it being at the same time of great importance for the achievement of good results that the temperature conditions are very accurately controllable. Finally it is of importance in a continuously performed process to avoid any deposit of for instance distillation products from a lacquer baking process in the furnace chamber or passages, and thereby avoid interruptions and expensive removal of such deposits.

In previously known methods for the heat treatment of surface coating on one or more continuously moved strips and in previously known furnaces for the performance of such treatment, the above conditions are only partly or poorly fulfilled and the purpose of the present invention consequently is to overcome the said inconveniences. It is hereby presumed that possible volatile components of the coating are substantially removed in advance.

According to the invention this is achieved by subjecting the strip material and the surface coating to the influence of one and the same continuously circulating, heated gas flows which is step-by-step subdivided in branch flows which in one of the divisional steps are in pairs acting upon the strip in opposite or substantially opposite directions.

Conveniently, the gas flow is subdivided in the following manner:

Firstly, the main flow from the pressure side of the circulating apparatus is divided into two partial flows which are fed to opposite ends of the furnace casing. Here each of the said partial flows is once more subdivided into two branch flows (flow pair) which are fed into the furnace chamber in opposite or substantially opposite directions against the side edges of the running strip from openings in the sides of the furnace chamber, preferably in such a manner that the top and lower faces of the strip or strips are simultaneously subjected to the influence of the flows.

In this manner a favourable turbulence is obtained and the effect of the same is enhanced thereby that the gas so combined is once more subdivided into two partial flows which are leaving the furnace chamber in directions substantially from the side edges of the strip through openings situated opposite each other in the sides of the furnace chamber, whereupon the partial flows are again combined and fed to the suction side of the circulating apparatus.

The subdivision system described, which is characteristic to the method of treatment according to the invention, has proved very favourable with regard to the obtaining an efficient heat transfer and a very accurate control of the temperature of the strip and of the coating, and consequently of the characteristics of the strip material and the coating proper.

The heating of the circulating gas flow preferably is

effected outside of the treatment zone proper and also outside of the furnace casing proper, the various partial and branch flows being then combined into a main flow.

Obviously, the method may be applied to a plurality of simultaneously moved strips and the furnace to be described may be used for the simultaneous treatment of a plurality of strips which preferably are running one beside the other.

A furnace adapted for the performance of the method according to the invention may preferably be made with an elongated furnace casing provided with longitudinal passages separated from the furnace chamber proper. The said passages are at one end communicating with a gas path from the pressure side of a circulating apparatus, and are at the other end opening into the furnace chamber proper through which the strip to be treated is moved in the direction of length of the furnace chamber, whereas the suction side of the circulating apparatus is communicated with a gas path directly leaving the furnace chamber.

The longitudinal passages which are separated from the furnace chamber proper preferably extend from the middle of the length of the furnace casing to points adjacent to the ends of the same, and the evacuation openings, leading into the gas passage communicating with the suction side of the circulating apparatus are also situated about the middle of the length of the furnace chamber.

The said longitudinal passages which extend to points adjacent to the ends of the furnace casing, open into the furnace chamber through openings which are situated opposite each other in the side walls of the furnace chamber. Conveniently, the passage openings are so made as to cause the gas flows directed against the side edges of the strip to turn slightly in the direction of the respective furnace end, and also so that both strip surfaces are influenced simultaneously. Hereby, both strip surfaces are also subjected to substantially equal pressures whereby the strip is not subjected to any "flickering." Of the same reason, the suction openings are preferably located substantially opposite to the side edges of the strip.

In order to avoid the arrangement of any sources inside of the furnace chamber proper or in direct communication with the same, for the purpose of heating the circulating gas flow, one or more heating elements are arranged in a separate heating chamber (heating battery) outside of the furnace casing in the gas path between the pressure side of the circulating apparatus and the inlets to the longitudinal passages.

In the heat treatment of continuously running strips it is often desirable and necessary to make the strips run freely through the treatment furnace, as a contact between the strip faces and conveyors or other feeding or supporting means may damage the strip surfaces or the coating of the same. This especially is the case with strips of comparatively soft material such as aluminium coated on both surfaces. In relatively long furnaces a freely suspended strip will, however, due to gravity give an excessively great sag and consequently require a great furnace height. A characteristic feature of the present invention consequently resides in such a form of the side walls of the furnace chamber that the lower portion of the same are obliquely or archedly merging into the furnace bottom whereby the strip by a possible excessive sag is only contacting the furnace walls by the side edges of the strip so that the strip may pass through the furnace without any damage to the surfaces.

By the simultaneous passing of a plurality of strips, the furnace bottom may be subdivided into more sections, each being formed as described above.

The accompanying drawing schematically illustrates an embodiment of a furnace according to the invention.

Figure 1 is a vertical longitudinal sectional view through the furnace installation.

Figure 2 is a partial horizontal sectional view through one end of the furnace.

Figure 3 is a vertical sectional view along the line III—III of Figure 1.

3

Figure 4 is a vertical sectional view along the line IV—IV of Figure 2.

In the drawing, 1 is the furnace chamber through which the strip 2 is moved in the direction of the arrow indicated in Figure 1. The furnace casing is heat insulated at 3 and is provided with a longitudinal horizontal partition 4 in the top portion, whereby longitudinal passages 5 are formed along the roof of the casing. Further, the furnace is provided with a gas supply passage 6 to the passages 5 and the distribution of the gas from the passage 6 to the passages 5 to each side of the passage 6 is effected by means of an adjustable guide shield 7 cooperating with a baffle ridge 8 on which the shield 7 is pivotably mounted.

At the other end, the gas flow through each of the passages 5 is, by means of a partition 9, subdivided into two branch flows 10, which under a deflection of 180° (Figure 4) are fed into the furnace chamber through passages 11, extending slightly obliquely inwardly from the ends and sides of the chamber 1 (Figure 2). At a point about the middle of the length of the chamber 1, slotlike suction openings 12 are arranged in the side walls, i. e. essentially opposite to the side edges of the strip 2, the said openings 12 being in communication with a suction passage 13 carrying the entire gas flow to the suction side of a fan 14, the pressure side of which is communicating with a conduit 15 carrying the gas flow to a heating battery 16, of conventional design which may be electric, from which the gas flow is again carried through the passage 6 to the passages 5.

In such a construction which provides for a completely closed heating gas circuit, it is presumed that the coating applied to one or both surfaces of the strip 2 does not, during the heating process, give off any volatile components. In certain cases, however, small quantities of such volatile components may be present, for instance such released by distillation during the treatment in the furnace. In order to remove such impurities from the gas flow, a blow tube 17 is arranged on the pressure side of the fan 14, the tube 17 being provided with a flap 18. A corresponding addition of fresh gas must then be supplied. If air is used as a heating gas, such supply may be effected through the openings through which the strip 2 is entering and leaving the treatment chamber. By the use of other heating gases suitable provisions must be made for additional supply of gas from an external source.

In the furnace described, no heating gas loss of any importance normally appears at the open ends of the furnace chamber, as all gas flows are balanced with regard to pressure.

The furnace may with great advantage be used for the purpose of baking, polymerisation, of a lacquer coating on metal strips, when the volatile components (the solvents of the lacquer) are removed in a previous heat treatment, and the present method and furnace provides for the possibility of obtaining baking periods of unusually short duration at the baking of lacquers, such as those used in the canning industry. Such lacquers usually require a stay period of upwardly to 8 to 15 minutes in the baking zone of the lacquering furnace, whereas the method and furnace according to the present invention enable the use of stay periods of a duration of about 1 minute and even less. Consequently the strip speed is very high, even by a comparatively small furnace length, and the production capacity correspondingly improved.

As an example it may be mentioned that the strip speeds of 15 to 30 m./min. and a stay period in the baking furnace of a duration of about ½ to 1 min. have been used in practice, at a maximum strip and lacquer temperature which, for instance for lacquers based on phenole may be within the range of 230 to 270° C., preferably at about 250° C. Under such conditions any deposition on the furnace walls, in the passages, etc., are avoided, and at the termination of very long operation periods, the interior of the furnace has presented itself as clean as when the operation started.

As to the meaning of the expression "step-by-step subdivision," this is intended to define that the flow is firstly

divided into two partial flows, each of which is then divided into two sub-partial flows and so on, all the said flows being then reunited and fed to the input of the blower.

5 We claim:

1. In a method for the simultaneous heat treatment of coatings on opposite sides of a strip of material, the steps including passing the strip freely continuously through a chamber from inlet to discharge thereof, introducing hot gas in a generally horizontal direction across the strip on each side of the strip and from opposite edges of said strip immediately upon its entering into said chamber, flowing the hot gas by turbulence over the surfaces of the strip as it advances to approximately mid-length of said chamber, extracting said hot gas from the sides of said chamber at approximately mid-length thereof, flowing additional hot gas by turbulence over both surfaces of the strip as it continues to advance from mid-length to discharge of said chamber, said last mentioned turbulent flow being derived from the introduction of hot gases in a generally horizontal direction across the strip, on each side of said strip and from opposite edges of said strip, said gases being extracted from said chamber at approximately mid-length thereof.

2. The method of claim 1, in which the hot gas introduced at the entrance and discharge of the chamber is treated by the steps of recirculating the gas extracted from the furnace at mid-length thereof through a fan, passing the gas through a heat exchange device to increase the temperature thereof, dividing the flow of hot gas from the heat exchange device into two streams, one to be led to the entrance end of the chamber, the other to the discharge end of the chamber, and subdividing each of these streams into the two sub-streams at each end of the chamber where the gases are introduced into the chamber in order that all the gas introduced into the chamber will be at the same temperature.

3. The method of claim 1, in which the strip is coated with phenolic resin lacquer and baked in the chamber at a temperature of from 230° C. to 270° C.

4. A furnace for simultaneous heat treatment of surface coatings on a strip of material comprising an elongated horizontal furnace chamber, hot gas circulating means comprising a blower to deliver hot gas into passages separated from the chamber, said passages being so arranged as to deliver the hot gas into the chamber in a generally horizontal direction from each side of and adjacent each end of said chamber, and further passages arranged at the sides of and mid-length of said chamber to remove the hot gas from said chamber and deliver them to the blower suction.

5. The furnace of claim 4, in which the side walls of the furnace are spaced to give a minimum clearance of the strip as it passes through the furnace.

6. The furnace of claim 5, in which the side walls converge downwardly from the level at which the strip of material normally passes in order that the edges only of the strip will strike the furnace walls in case the strip sags materially below its normal position.
